UNITED STATES PATENT OFFICE.

HENRY J. GAISMAN, OF NEW YORK, AND CONRAD SCHUMACHER, OF LYNNBROOK, NEW YORK, ASSIGNORS TO AUTAN CORPORATION, OF DOVER, DELAWARE, A CORPORATION OF DELAWARE.

BLADE-BACKING MACHINE.

Application filed March 23, 1923, Serial No. 627,094. Renewed November 16, 1926.

Some safety razor blades are provided with strips, called backings, clamped along the back edges remote from the cutting edges, which provide means for retaining 5 the blades in safety razor frames or holders as well as stiffening the blades.

The object of our invention is to provide means to secure backing pieces in successive order along a strip of steel to be used for 10 razor blades and to sever the strip successively between adjacent backing pieces, so that each time the strip is severed a blade having a backing attached thereto will be delivered.

15 Our invention comprises novel details of improvement that will be more fully herein-after set forth and then pointed out in the claims.

Reference is to be had to the accompanying drawings forming a part hereof, wherein

Fig. 1 is a plan view of a machine embodying our invention;

Fig. 2 is a cross section on line 2, 2, in Fig. 1;

25 Fig. 3 is a partly sectional end view looking from the right hand side of Fig. 1;

Fig. 4 is an enlarged partly sectional detail plan view of a strip severing device;

Fig. 5 is a section on line 5, 5, in Fig. 4;

30 Figs. 6 and 7 are details of crank means;

Fig. 8 is a sectional detail of the receiver for blades on line 8, 8, in Fig. 2;

Fig. 9 is a detail side view looking in the direction of the arrows 9 in Fig. 1;

35 Fig. 10 is a plan view of Fig. 9;

Fig. 11 is a partly sectional detail view of driving means on line 11, 11, in Fig. 3;

Fig. 12 is a sectional detail of means to feed backing pieces to the blade strip, on 40 line 12, 12, in Fig. 2;

Fig. 13 is a section on line 13, 13, in Fig. 12;

Fig. 14 is a detail of the blade strip having backs applied before being severed, and

45 Fig. 15 is a sectional detail on line 15, 15, in Fig. 4.

Similar numerals of reference indicate corresponding parts in the several views.

The main frame of the machine may be 50 of any suitable construction being shown comprising a table-like top 1, having legs 1^a. A main driving shaft is indicated at 2 jour-

naled in suitable bearings on the frame and provided with a loose pulley 3, preferably having a weighted fly wheel 4, clutch means, 55 hereinafter described, being provided to connect and disconnect the pulley with shaft 2. A strip for the blades is indicated at A, shown provided with spaced notches a along the edge opposite the cutting edge a'. The 60 machine is provided with guiding means for the strip, shown comprising spaced rollers at 5, where the strip enters the machine, and spaced stationary guides at 6, 7, and rolls at 8 between guides 6 and 7. The rolls may 65 be spring-pressed toward each other by means of springs 9 pressing blocks or slides 10 that carry the rolls, (Fig. 1). The backing pieces are indicated at B, and are shown stacked in a guideway or magazine 11 de- 70 pending from frame 1. The backing pieces rest upon a feeding block 12 which is normally actuated to force the backing pieces toward the blade (Fig. 12). The block 12 is slidably guided in the magazine and is 75 shown provided with a flexible connection or rope 13 passing over a pulley 14 and having a weight 15 to elevate the block. A removable wall 11^a is provided on the magazine to permit charging the latter to retain the 80 backing pieces slidably therein. A spring-pressed catch 16 is pivotally carried by the magazine adapted to engage and retain the lower end of wall 11^a, (Fig. 3). At the upper end of the magazine spaced stops 11^b 85 are provided against which the upper edges of the gutter-like backing pieces B are pressed by the block 12 and its weight 15 so that the blade strip A may travel through the uppermost backing piece, (Fig. 12). 90

Means are provided to feed the strip A step by step and to feed the backing pieces B successively to a position to be clamped in successive order, end to end, along the adjacent edge of said strip. A stop 17 on one side of strip A, near the guide rolls 5, is opposed by spring-pressed dog 18 that is carried by a movable member 19 supported at 20 and pivotally connected at 21 with a bell-crank lever 22 pivotally supported at 23, (Fig. 1). The lever 22 is engaged by an adjusting screw 24 carried by an arm 25 secured on a slide 26 mounted in a guideway 27 on the main frame. A lever 28 is piv-

totally connected with arm 25, at 29, and is pivotally supported on the main frame at 30 and provided with a projection 31 cooperative with a cam 32 for rocking the lever 28. 5 When lever 28 is rocked in one direction the lever 22 will be rocked to cause dog 18 to slide along strip A until it enters an adjacent notch α and will continue so as to feed said strip an amount equal to the desired length 10 of a blade, and on the reverse stroke of said lever said dog will slide reversely to engage the next notch in strip A, and so on successively for each blade to be backed. At 33 is a feeder for the backing strips comprising 15 a pair of jaws spaced to receive the strip A between them, said jaws being secured to a slide 34 guided in ways at 35, (Figs. 1 and 3). The feeder jaws 33 are adapted to reciprocate along the strip A to feed the 20 backing pieces B from the magazine 11 into position between opposing jaws 36, adapted to squeeze the edge portions of the backing pieces tightly against strip A. To reciprocate the feeder jaws 33 the slide 34 is connected by a link 37 with a rock arm 38 that is pivotally supported upon a bracket 39 secured upon the main frame. The arm 38 is provided with a projection 40 cooperative with a cam 41 secured on a shaft 42 carried 25 in bearings upon bracket 39. The shaft 42 is shown provided with a gear 43 in mesh with an idle gear 44 suitably journaled in the main frame, and gear 44 is in mesh with a gear 45 secured on shaft 2, (Figs. 1 and 3). The cam 32 is secured upon shaft 42. Each time the feeder jaws 33 are reciprocated back and forth the clamping jaws 36 are also reciprocated toward and from each other in timed relation to the feeding of the backing pieces B between the last named jaws. 30 The jaws 36, preferably having hardened end pieces, are slidable toward and from each other in guideways 46 on frame 1, and operated by means of toggle levers comprising links 47 pivotally connected with jaws 36 and pivotally connected at 48 to links 49 pivotally supported at 50. The pivots 50 are preferably carried by adjustable blocks 51 adapted to be adjusted by screws 52 and 35 retained in set position by bolts or screws 53, (Figs. 1 and 3), to regulate the approach of jaws 36. The pivots 48 are connected with depending links 54 pivotally connected at 55 with straps 56 enclosing eccentrics 57 secured on shaft 2. When said shaft is rotated the toggle levers or links 47, 49 will be operated to cause the jaws 36 to approach a backing piece B fed by feeder 33 to clamping position along strip A between said jaws, 40 whereby the jaws squeeze the sides of the backing piece against the strip A securely and thereupon the jaws 36 recede. During the separation of said jaws the strip A is fed a step and a backing piece B is also fed, and the jaws again squeeze the backing 45

piece upon strip A, and so on successively, whereby the backing pieces are secured in spaced relation along strip A, as indicated in Fig. 14, the backing pieces at their ends abutting one another, or approximately so. 70

After the backing pieces have been applied upon the strip A the latter is severed, step by step, at points between the adjacent ends of two backing pieces to produce the final blades. A block 1^c on table 1 supports 75 the guides 7 and carries a reciprocative punch bar 58 in a member 59, which punch bar has a hardened nose or tool 60 operative transversely respecting guides 7 to engage the strip A to sever or break it by a blow 80 against the same, (Figs. 1, 4 and 5). One of the guide members 7 is spaced at 61 for the entrance of the nose 60. To resiliently resist the blow of the tool an anvil is provided at 62, loosely mounted respecting the 85 guideway 7 and backed by a spring 63. Beneath the guideway the backings B travel on a guiding strip 64, (Figs. 5 and 15). A reciprocative bar 65 slides in a guideway 66 in block 1^c and carries a spring-pressed 90 dog 67 that is adapted to engage in the notches of the strip A between the backing pieces B to feed the same. A hardened pin 68 extends through the dog 67 to engage the backings B, (Fig. 15). The dog 67 is pivotally supported at 67^a in such a manner that when bar 65 moves in the direction of the arrow α in Fig. 4, the dog will engage a notch α of strip A to feed the latter, and when said bar moves in the opposite direction the dog will slide along a backing piece to engage the next notch α , and so on successively. The operating end of dog 67 travels in a slot 7^a in one of the guide parts 95 100 105 110 115 120 125 130 135 140 145 150 155 160 165 170 175 180 185 190 195 200 205 210 215 220 225 230 235 240 245 shown provided with a slot 58^a in which the arm 79 is located, (Fig. 5). The arm 79 is secured to bar 65 and extends parallel therewith so as to be reciprocated with said bar, (Fig. 4). The projection 81 is adapted to advance toward arm 79 without interference by surface 80 when the parts are in the position to sever strip A, substantially as indicated in Fig. 4, when dog 75 has released the bar 58. When arm 79 is moved toward the bottom of Fig. 4 the surface 80 will be moved into engagement with projection 81 to withdraw bar 58 and to cause engagement of its stop 77 with dog 75. When arm 79 moves in the last named direction a projection 79^a on said arm will engage a pawl 82 pivoted on dog 75, at 83, and spring pressed toward arm 79 by a spring 84, being limited in such direction by a stop 85, (Fig. 4). When arm 79 moves in the last named direction its projection 79^a by engagement with pawl 82 will cause dog 75 to tilt to release bar 58, whereupon the latter will be moved suddenly toward strip A to sever the latter between two backings B, and continued movement of arm 79 will cause release of its projection 79^a from pawl 82, as in the position shown in Fig. 1, whereby dog 75 may return to position to again engage stop 77 when surface 80 of arm 79, being engaged with projection 81, again moves bar 58 outwardly. It will be understood that each time that bar 65 moves in the direction of the arrow α the dog 68 will feed strip A a step equal to the length of a blade to bring the meeting edges of two backing pieces B in opposition to the nose 60 of bar 58, as indicated by the dotted line b in Fig. 14, and when the bar 65 moves reversely the dog 68 will slip along a backing piece B, the dog 75 will release bar 58 to strike a blow against strip A to sever the strip, as indicated at c in Fig. 14, and the surface 80 will operate on projection 81 to reset bar 58 to be retained by dog 75 for the next working stroke, so that when bar 65 again advances the bar 58 will remain set while dog 68 feeds strip A for another blade, and so on successively.

To resiliently limit the striking distance of bar 58 its head 74 is adapted to engage a spring pressed cap 86 mounted slidably upon a hub 87 at the side of block 1^c. Springs 88 interposed between said hub and cap normally force the latter outwardly. A screw or plug 89 carried by block 1^c adapted to engage recesses 90 in cap 86 retains said cap adjustably to resist the blow of head 74 and limit the advance of the bar 58 to the work.

The bar 65 may be reciprocated in any suitable way. We have shown a link 91 pivotally connected with bar 65, which link is pivotally connected with a crank-pin at 92 carried by shaft 42. To regulate the

throw of the crank-pin the same is shown carried by a block 93 adjustable radially in a guideway 94 in a disk 95 secured upon shaft 42 and held in set position by screw 96, (Figs. 2, 6 and 7).

The blades having the backings B secured thereto may be delivered from the machine in any suitable way. By preference the blades are delivered into a receiver 97 that is removably mounted upon a carriage 98 75 slidable along guides 99 carried by frame 1, (Figs. 1 and 2). The receiver 97 is shown provided with spaced transverse strips 97^a between which the blades are fed. The carriage is normally fed in the direction of the arrow y in Fig. 1, for which purpose a flexible connection or rope 100 is attached to the carriage and passes over a pulley 101 from which it depends and is provided with a weight 102 to pull the carriage. The carriage is provided with a longitudinally disposed rack 103 adapted to be engaged by dog 104 carried by a lever 105 pivoted at 106 and pressed by a spring 107 toward the rack. The lever has a projection 108 in the path of blades entering a space between adjacent strips 97^a. When a desired series of blades have entered such space and have been finally pushed against the projection 108 the latter will move the dog 104 out of engagement with rack 103, whereby the weight will pull the carriage, and when the said blade has passed from the projection 108 the dog 104 will snap back against the rack to stop the carriage with the next space between strips 97^a in position to receive blades, and so on as the spaces between said strips are filled with blades. When the receiver 97 is charged with blades, or substantially so, it may be removed from the carriage and another replaced, and the carriage moved back to the initial position, and so on.

In order to automatically stop the machine when the receiver and its carriage have reached the limit of travel with blades in the spaces between the last series of strips 97^a, we provide means to automatically release the clutch between shaft 2 and pulley 3 before referred to. A member 109 is keyed on shaft 2 and provided with a pin 110 pressed by spring 111 to engage one or more notches in wheel 4. A dog or finger 112 is pivotally supported at 113 on a bracket 114 secured upon the main frame, the free end of which dog is operative in an annular groove 109^a in member 109, (Figs. 2 and 11). The upper end of dog 112 is bevelled at one side at 112^a, (Fig. 3), to engage block 115 slidable in way 116 of member 109 and provided with an inclined surface 115^a to engage dog 112. Said block is connected with pin 110 so that when the block engages dog 112 the pin will be withdrawn to release member 109 from the drive pulley, thereby to stop shaft 2 and the ma-

chine. A spring 117 normally pushes dog 112 into position to engage block 115. A link 118 is pivotally connected with dog 112 and with a rock arm 119 pivotally supported upon bracket 114, (Fig. 2), which link is pivotally connected with a rod 120 that is pivoted at 121 to a lever 122 pivoted on the main frame at 123, (Fig. 1). The free end of lever 122 extends in position 10 to be grasped by the operator through a guide at 124, where it is adapted to be engaged by a stop dog 125 when the machine is to operate, (Figs. 1, 9 and 10). Stop dog 125 is carried by or formed with a lever 15 125^a pivoted at 126 and normally pressed upwardly by a spring 127, the dog 125 being stopped by guide plate 124^a. A button or hand piece 128 is over lever 125^a in position 20 to be readily engaged and cooperates with said lever to depress it when it is desired to stop the machine manually. When the free end of lever 122 is moved to the right in Figs. 1, 9 and 10 it will shift dog 112 to withdraw it from the path of block 115 and 25 said lever will be engaged by stop dog 125, and pulley 3 will drive shaft 2. If lever 125^a be pushed downwardly the dog 125 will release lever 122 and spring 117 will move dog 112 into the path of block 115 and correspondingly shift lever 122, stopping the 30 machine. While stop lever 125 may be operated by means of button 128 it is also operative by means of a bell-crank lever 129 pivoted at 130 and pivotally connected by 35 a rod 131 with an angle-lever 132 pivoted at 133, (Fig. 9). An upstanding arm 132^a has a laterally disposed portion 132^b located in the path of a stop 134 on carriage 98. Stop 134 is preferably in the form of a 40 screw to permit adjustability in respect to lever arm 132^b, (Fig. 10). When the machine is operating and lever 132 is retained by stop dog 125, lever arm 132^b will be in register with stop 134 of carriage 98. When 45 razor blades have been charged into the space between the last pair of strips 97^a of the receiver 97 and the carriage 98 starts to move, the stop 134 will engage lever arm 132^b, causing lever 129 to rotate, which will 50 depress lever 125^a causing stop 125 to release lever 122 and spring 117 will thereupon move dog 112 into the path of block 115 to unshift the clutch pin 110 and stop rotation of shaft 2.

55 The operation may be described as follows. To commence operations the strip A is fed between the rolls 5 through feeder 33, between the separated jaws 36, thence between rolls 8, 9 and through guide 7 a 60 suitable distance to be engaged by dog 67, and the magazine is charged with backing pieces B. Lever 122 is shifted to be held by stop 125 and the machine will operate. The dog 18 will engage a notch *a* in strip A to 65 assure that the latter assumes a proper

position respecting jaws 36. Feeder 33 will operate to feed a backing piece B along strip A in proper position between jaws 36. Jaws 36 will approach to squeeze the sides of the backing piece B securely against strip A 70 and will recede to free the piece B. Bar 65 will be retreating from bar 58 and dog 75 will release bar 58 to cause it to sever strip A, and before the limit of such travel of bar 65 the surface 80 will engage projection 81 75 to reset bar 58 to be held by dog 75 out of the path of strip A. Corresponding operations occur successively for each blade to be backed and cut from strip A, such strip pushing the cut off blades through guide 7 80 into the receiver 97.

The strip feeding operations of dogs 18 and 67 are independent of but with relation to each other. The dog 18 has a limited strip feeding movement to assure the proper 85 position of strip A between jaws 36 to receive the successive backing pieces B. When the cutting edge is formed on a steel strip A and the spaced notches *a* formed therein 90 before the strip is hardened or tempered the metal is liable to shrink in some places when hardened thereby disarranging the original spaced relation of some of the notches *a* with relation to one another. The feeding dog 18, by sliding a short distance 95 along the strip will enter the notches *a* successively and feed the strip, if necessary, such a distance with relation to jaws 36, as will rectify any variation of distance between notches *a* so that strip A will always 100 assume a correct initial position for reception of backing pieces B respecting jaws 36 so that the pieces B will always be properly positioned upon strip A. With such initial setting of backings B upon strip A the dog 105 67 will feed the strip finally, step by step, for each blade, the required distance independent of the initial setting of the strip by dog 18.

The machine will apply the backings to 110 strip A and cut off the finished backed blades successively, accurately, automatically and expeditiously.

Having now described our invention what 115 we claim is:

1. A machine for backing blades comprising means to feed a strip, means to apply backings thereto successively, means to clamp the backings upon the strip, and means to sever the strip between the backings to produce blades.

2. A machine for backing blades comprising means to feed a strip, means to apply backings thereto successively, means to clamp the backings upon the strip, means to sever the strip between the backings to produce blades, a receiver for the blades, means to move the receiver step by step from blade receiving position, means to drive the machine including clutch devices,

- and controlling means for the clutch devices operative by the receiver moving means to stop the machine.
3. A machine for backing blades comprising means to move a strip step by step, clamping means on opposite sides of the strip, means to supply backings to the strip, means to feed the backings successively to said clamping means, mechanism to actuate the clamping means to secure the backings successively and adjacent on the strip, and means to sever the strip between adjacent backings.
4. A machine for backing blades comprising means to guide a strip, clamping means on opposite sides of the strip, devices to initially feed the strip successively to definite positions relative to the clamping means, means to supply backings to the strip, devices to feed the backings successively to the clamping means, devices to sever the strip between backings, and means to feed the strip to the severing devices and to actuate the latter to sever the strip successively.
5. A machine for backing blades comprising means to guide a strip, devices to feed the strip step by step, a magazine for backings provided with means to propel the backings to the strip, clamping devices for the backings, a feeder for the backings to feed them successively to clamping position along the strip, means to actuate the feeder, and means to sever the strip successively between backings thereon.
6. A machine for backing blades comprising means to guide a strip, means to feed the strip step by step, clamping jaws on opposite sides of the strip, means to actuate the clamping jaws, a magazine for backings provided with means to deliver the backings to the strip, a reciprocative feeder to push the backings from the magazine to position between the jaws successively, and means to sever the strip successively between backings thereon.
7. A machine for backing blades comprising guiding means for a notched strip, a dog to engage said notches, means to reciprocate the dog along the strip for initial adjustment of the latter, clamping means on opposite sides of the strip spaced from the dog, mechanism to operate the clamping means, means to supply backings to the strip, a feeder to feed the backings successively to the clamping means, severing devices for the strip, and means to actuate the severing devices successively after the clamping means have clamped backings upon the strip.
8. A machine for backing blades comprising guiding means for a strip, clamping jaws on opposite sides of the strip, means to actuate the clamping jaws, a dog to initially feed the strip, a movable member carrying the dog, a lever to operate said member, means to actuate said lever, a supply for backings, means to feed backings successively between said jaws along the strip, means to sever the strip between backings thereon, means to actuate the severing means successively, and means to feed the strip with its backings step by step after each operation of the severing means.
9. A machine for backing blades comprising guiding means for a strip, clamping jaws on opposite sides of the strip, mechanism to reciprocate said jaws toward and from the strip simultaneously, a magazine for backings, means to maintain the backings pressed toward the strip, a feeder to push backings along the strip between the jaws while the jaws are separated, devices to sever the strip between backings thereon, and means to feed the strip step by step respecting the severing devices after the jaws have secured backings on the strip.
10. A machine for backing blades comprising guiding means for a strip, clamping jaws on opposite sides of the strip, a drive shaft, means to drive said shaft, clutch means to connect and disconnect the shaft and the driving means, jaws on opposite sides of the strip, devices operated by said shaft to reciprocate said jaws toward and from the strip, a magazine for backings comprising means to feed the backings toward the strip, a feeder to push the backings successively between the jaws, mechanism operated by said shaft to actuate the feeder, cutting means to sever the strip between backings, means to feed the strip step by step, mechanism operated by the shaft to actuate the severing and feeding means, a carriage movable transversely with respect to the strip, means to move the carriage, means to check the movement of the carriage provided with a projection in register with the strip, and a receiver upon the carriage for blades, said projection being in position to be engaged by blades in said receiver to release the carriage.
11. A machine for backing blades comprising guiding means for a strip, clamping jaws on opposite sides of the strip, a drive shaft, means to drive said shaft, clutch means to connect and disconnect the shaft and the driving means, jaws on opposite sides of the strip, devices operated by said shaft to reciprocate said jaws toward and from the strip, a magazine for backings comprising means to feed the backings toward the strip, a feeder to push the backings successively between the jaws, mechanism operated by said shaft to actuate the feeder, cutting means to sever the strip between backings, means to feed the strip step by step, mechanism operated by the shaft to actuate the severing and feeding means, a carriage movable transversely with respect to the strip, means to move the carriage, means to check the movement of the carriage provided with a projection in register with the strip, and a receiver upon the carriage for blades, said projection being in position to be engaged by blades in said receiver to release the carriage.

to the strip, means to move the carriage, means to check the movement of the carriage provided with a projection in register with the strip, a receiver upon the carriage for blades, said projection being in position to be engaged by blades in said receiver to release the carriage, devices to control the clutch including a lever, a stop for said lever to retain the clutch in operative relation to the shaft, and means operative by the carriage to release the stop from the lever.

12. A machine for backing blades comprising guiding means for a strip, clamping jaws on opposite sides of the strip, a drive shaft, means to drive said shaft, clutch means to connect and disconnect the shaft and the driving means, jaws on opposite sides of the strip, devices operated by said shaft to reciprocate said jaws toward and from the strip, a magazine for backings comprising means to feed the backings toward the strip, a feeder to push the backings successively between the jaws, mechanism operated by said shaft to actuate the feeder, cutting means to sever the strip between backings, means to feed the strip step by step, mechanism operated by the shaft to actuate the severing and feeding means, a carriage movable transversely with respect to the strip, means to move the carriage, means to check the movement of the carriage provided with a projection in register with the strip, a receiver upon the carriage for blades, said projection being in position to be engaged by blades in said receiver to release the carriage, devices to control the clutch including a lever, a stop for said lever to retain the clutch in operative relation to the shaft, a second lever cooperative with a catch to cause it to release the first named lever, and a third lever connected with the second named lever and provided with an arm to be actuated by the carriage to cause release of the stop from the first named lever.

13. A machine for backing blades com-

prising means to guide a strip, a magazine for backings beneath the strip, a member in the magazine to support the backings, means normally moving said member toward the strip, jaws to squeeze the backings against the strip, a feeder to feed backings from the magazine to position along the strip between the jaws, means to operate the feeder, means to actuate the jaws, devices to sever the strip between backings thereon, and mechanism to feed the strip step by step.

14. A machine for backing blades comprising means to guide a strip, a magazine for backings beneath the strip, a member in the magazine to support the backings, means normally moving said member toward the strip, jaws to squeeze the backings against the strip, a feeder to feed backings from the magazine to position along the strip between the jaws, means to operate the feeder, means to actuate the jaws, devices to sever the strip between backings thereon, and a reciprocative bar having a dog to feed the strip, the severing devices having a dog to control the cutter, said bar having means to control the second named dog and the cutter during reciprocations of the bar.

15. A machine for making razor blades comprising means for feeding a strip, means for securing backings one after another along an edge of the strip, and means for severing the strip between the backings to produce individual blades having a backing.

16. A machine for making razor blades comprising means for feeding a strip step by step, means for applying a backing along an edge of the strip at each stop thereof, and means for severing the strip between the backings to produce individual blades each having a backing along an edge thereof.

Signed at New York city, county and State of New York, this 21st day of March, 1923.

HENRY J. GAISMAN.
CONRAD SCHUMACHER.
